UNITED STATES PATENT OFFICE.

HARRY W. KULP AND MARTIN C. DELLINGER, OF LANCASTER, PENNSYLVANIA.

HEAVY-DUTY VALVE-SPRING LIFTER OR COMPRESSOR.

Application filed July 22, 1927. Serial No. 207,692

This invention relates to valve spring lifters or compressors for use in compressing or lifting the lower ends of the valve springs as arranged about the valve-stems of poppet 5 valve type internal combustion engines to permit the retaining pin or key to be easily removed or reinserted in removing or replacing the valves and their stems incident to the grinding of the valves or their removal or re- 10 placement or adjustment for any reason, and is primarily intended for use with very strong springs of this nature as used on large engines such as employed in large motor trucks, busses, tractors and the like.

15 The primary objects of this invention are to provide a very rugged tool with great leverage so as to be very easily operated, notwithstanding the great strength of the spring, to compress the latter; to provide a C-shape 20 tool so reinforced as to overcome the tendency to spread or elongate under pressure of the spring; to provide a convenient handle for positioning the tool in close association with an operating handle to facilitate in general 25 the manipulation of the tool; to provide in such a tool an offset lever construction to avoid engine parts; to so locate said positioning handle and operating handle or lever as to facilitate the use of the tool by increasing 30 the range of vision about both the foot and the jaw whereby said tool may be easily and quickly operated by a single operator or mechanic, without aid, to lift or compress such 35 valve springs, in operative position about the valve stems of such large engines; to provide a convenient lever lock; to provide in such a 40 tool an adjustable bearing and supporting member or foot for bearing against the top of the valve as the frame with its adjustable 45 jaw moves in accordance with the levers; to combine in such a tool means for compressing a free valve spring as a preliminary to its insertion into operative position about a valve 50 stem, and to provide special details in the latter means, all of which objects, among others, are accomplished by the construction, combination and arrangement of parts all as hereinafter more particularly set forth, described 55 and claimed.

60 In this application I show and describe only the present preferred embodiment of my invention, simply by way of illustration of the practice of my invention as by law required. However, I recognize that my invention is capable of other and different em- 65 bodiments, and that the various details there-

of may be modified in various ways, all without departing from my said invention; therefore, the drawing and description herein are to be considered simply as illustrative and not 60 as exclusive.

In the accompanying drawings made to scale from an actual full size commercial valve spring lifter or compressor:

Figure 1 represents a side elevation of a device embodying our invention as applied to a valve spring and valve of an engine, all indicated in dotted line, the device being operatively positioned and open;

Figure 2, a similar view of the device, closed 70 to lift or compress the spring;

Figure 3, a front elevation of the device;

Figure 4, a top plan view of the body, broken away, to show the reinforcing or bracing plates extending about the long curve of 75 the frame;

Figure 5, a fragmentary sectional view on the line 5—5 of Figure 1 looking in the direction of the arrows to show the construction and combination of the thrust links, parallel 80 movement links, frame and operating lever;

Figure 6, a fragmentary section on line 6—6 of Figure 1;

Figure 7, a fragmentary section on line 7—7 of Figure 8;

Figure 8, a detail fragmentary side elevation of the levers, frame and supplementary free spring or compressor, showing a spring ready to be compressed;

Figure 9, a view similar to Figure 8, only 90 showing the spring compressed with the relative positions of the parts;

Figure 10, an enlarged, detail fragmentary view on the line 10—10 of Figure 11; and

Figure 11, an enlarged detail top plan, 95 partly broken away and sections of the post 34 with the keeper 37 thereon, the locking means of the latter being shown in operative position in elevation in solid lines and indicated by dotted lines in inoperative position.

100 In operating on the springs of the larger engines such as employed in large trucks, busses, etc., it has been usual, because of the great power of such springs and conditions bearing on accessibility to the springs, to employ a foot adapted to engage the upper face of the valve and a small arm carrying a jaw substantially in line with said foot, some leverage means for moving the jaw toward the foot to thereby compress the spring, and some means for locking the leverage means in such 110 position. Such a general construction per-

mits the employment of an arrangement of levers such as will give great leverage power.

However, the engines on which such valve spring lifters are to be used are quite large 5 and the lifters themselves are quite large, so that it has been difficult with the heretofore known lifters for one mechanic to raise or compress a valve spring of such an engine with such a lifter because it was so difficult to 10 get the jaw and foot in operative positions, since only one of them was within his range of vision from the position he had to assume in operating the tool, and as a consequence two mechanics have heretofore been necessary 15 to perform the job or when attempted by one mechanic much of his time has been lost in positioning one and then the other with repeated shifts of his own position, until finally both the foot and jaw could be moved and main- 20 tained in operative position until the mechan- ic could operate the tool.

The present embodiment has in view to provide such a heavy duty valve spring lifter in which the positioning handle and operat- 25 ing lever are both so located as to extend to one side of the engine so that the mechanic may stand on the ground and easily and quickly operate the tool while having full vision, without changing his position, of both 30 the foot and the jaw in operative position, so that one mechanic may easily and quickly operate the lifter to raise or compress a valve spring without need of any assistance what- soever.

35 However, while this feature is of value and important, considering our invention from one broad aspect, it is not of importance to other features of our invention which may be employed with an embodiment lacking this 40 feature.

Referring now in detail to the drawings, the frame or body, preferably of approximate spread C form, is preferably formed of two flat bent narrow plates or straps 1 of steel or 45 forged steel reinforced about the lower curve by two curved bracing plates or straps of steel or forged steel 2 located between said straps 1 and secured thereto by rivets 3 and 4, spacing blocks, washers, or fillers 5 being interposed between said bracing plates 2 about the respective rivets 3 and 4.

To the upper portion of this frame and extending on the outer side of the C a handle 6, having a bifurcated shank 7 having its extreme ends positioned between the plates 1 and 55 extending lengthwise thereof for an appreciable distance, is secured by the rivets 8 and 8^a at two points of the length of said plates 1 so as to be immovable with relation to said 60 frame.

Jaw members 9 are secured to the lower ends 10 of the respective plates 1 by means of screws 11, or equivalents, two screws 11 being used, for each jaw member 9 to hold it rigidly 65 in position. Such construction permits the

removal and replacement of said jaw mem- bers 9 whereby different sizes and forms of jaw members 9 may be used according as the circumstances may require, or the removal and replacement of a damaged jaw member 9.

The lower portions 10 of the plates 1 are re- 7 sili ent and free to flex from the rivet 4 to their extreme lower ends, and a screw 12 extending through one portion 10 and having screw- 7 thread engagement with the other portion 10 serves as a means for adjusting said portions 10 and their jaw members 8 toward and away from each other, as may be necessary accord- 7 ing to the size of the valve stem and any asso- 7 ciated parts.

Two parallel movement links 13 and 14 are pivoted on the rivets 8 and 8^a, respectively, at their outer end portions which extend between the bifurcations of the shank 7 of the position- 8 a ing pistol grip handle 6 and have their inner end portions pivotally, by pivot pins 15 and 15^a, connected respectively, to a long, flat sleeve 16, which has a transverse perforation and receives the shank 17 of the foot 18, said shank 17 being provided with a number of transverse perforations 19 adapted to be selec- 9 90 tively brought into registry with the trans- 95 verse perforation in the sleeve 16 to permit adjustment of the effective or operative length of the shank 17 as may be necessary for work on any particular engine, a cotter pin or equivalent 20 being inserted in the registering perforations in said sleeve 1 and shank 17 to prevent relative endwise movement between them after adjustment.

The distance between the rivets 8 and 8^a is approximately the same as the distance be- 100 tween the pivot pins 15 and 15^a, and the dis- 105 tance between the axis of the rivet 8^a and the axis of pivot pin 15^a is approximately the same as the distance between the axis of rivet 8 and the axis of pivot pin 15, and the length of said links 13 and 14 is such that in all po- 110 sitions of the links 13 and 14 the axial line of the shank 17 will intersect the jaw members 9. 110

A long operating lever 21 pivotally mounted between the plates 1 on pivot pin 22 at a point well above and in advance of the rivet 8^a is pivotally connected by pivot pin 23 to the thrust linkage means 24 pivotally connected by a pivot pin 25 to one of the parallel movement links, said pivot pin 23 being located closely adjacent to, and to the rear of, the pivot pin 22 pivotally connecting said lever 21 to the frame to give a powerful lever- 120 age and the pivot pin 25 will preferably be located almost directly below the pivot pin 22 to give a short, straight thrust.

In the embodiment illustrated the linkage means 24 straddles the link 14 and is pivotally 125 connected to the link 13 being thus of a bifur- cated type and it may consist, as illustrated, of two members, one arranged on each side of the links 14 and 13, having their lower ends connected by the pivot pin 25 passing through 130

the intervening portion of link 13, and having their upper end portions offset so as to lie flat against each other between the sides of the channeled, preferably sheet metal, lever 21 and held therein by the pivot pin 23 passing through the sides of said lever 21 and the intervening upper end portions of said members to pivotally connect them to said lever 21.

10 A little lock plate or catch 26 pivotally mounted on the shank 7 close to the plates 1 by a pivot pin 27 and slotted in registry with the bifurcation of shank 7 cooperates with a tongue 28 pivotally connected by pivot pin 29 to the lever 21 between the sides thereof, extending through the slot in said plate 26 and the bifurcation of shank 7 and having its outer edge notched at spaced intervals, as at 30, to lock the lever 21, and hence the links 13 and 14 in any one of a number of operative positions, the rear wall of the slot in the plate or catch 26 being adapted to fit in said notches 30 to hold said tongue 28 against reverse movement.

25 To hold said lock plate or catch 26 in operative position about its pivot 27 and with its rear end spaced from the shank 7 and handle 6, a little leaf spring 31 is employed, and this spring 31 may be in the form, as shown in the embodiment illustrated, of an integral bifurcated wire spring straddling the shank 7, having its legs wound one or more times about the pin 27 and then bent back and in contact with the lower face of said plate 26.

35 In operation, as the lever 21 is swung on its pivot 22 toward handle 6, the upper walls of the notches 30 will engage with the rear wall of the slot in the plate 26, which will thereby be depressed against the action of the spring 31, thus permitting the tongue 28 to slide on through the plate 26 and shank 7, but on the reverse movement of the tongue 28 the rear wall of the slot in the plate 26 will be in engagement with the lower face of one of the notches 30, so that the compressed valve-spring will act to cause a tighter grip of the plate 26 on the tongue 28.

The plate 26 may have a rearward extension 26^a to be depressed by the mechanic's thumb 50 to release the stem 28 to allow the parts to move back to original or open position.

From the foregoing it is obvious that with the jaw, comprised of jaw members 9, applied about a valve stem beneath its valve spring retaining washer or cup and with the foot 18 resting on the top of the valve, movement of the operating or handle lever 21 toward the pistol grip positioning handle 6 will cause a straight movement of the frame as a whole, including the jaw, toward the foot 18, the straight line intersecting the axes of rivets 8 and 8^a being maintained at all times parallel, or substantially parallel, to the straight line intersecting the axes of pivots 15 and 15^a, and reverse movement of the lever 21, the locking

means being released, will cause movement of the frame in the reverse direction away from the foot.

In order that the device may function also as a means for compressing free valve-springs so that they may be easily inserted and arranged in operative position, in accordance with usual present practice, by any suitable spring holding and positioning clip, not shown, the extreme upper forward or inner 75 end portions 32 of the plates 1 lie close together, one of them being inwardly offset, beyond the pivot pin 22, for that purpose, as at 33.

A post 34 pivotally connected to link 14 80 extends upward between the opposed faces of said end portions 32, has one edge formed with a number of spaced notches 30, and is of such thickness as to make a loose sliding fit between, and to be guided by, said opposed 85 faces of said end portions 32.

Said end portions 32 will be formed with registering transverse perforations 35 inward of the normal path of travel of the post 34, and a cotter pin 36, or equivalent, will be 90 inserted through said registering perforations to prevent the post 34 from swinging about its pivot 33 toward link 14 to an inoperative position.

Said end portions 32 may be formed also 95 with similar perforations 35^a in the same horizontal plane as perforations 35 and at a point nearer to the pivot pin 22, being spaced from the registering perforations 35 a distance approximately the same as, or slightly in excess 100 of, the width of the post 34, and, if desired, a cotter pin may also be arranged in these registering perforations to prevent any substantial swinging movement of the post 34 toward the pivot 22 of lever 21; however, this 105 is a matter mainly of personal preference, its use in some situations may be an advantage, but in most instances it may be omitted with no appreciable loss of efficiency, and the present embodiment as illustrated, while making 110 provision for its use, if desired, omits it.

A little removal compressor head 37 of channel sheet metal centrally slotted to allow the passage therethrough of the post 34 and provided with oppositely presented flanges 115 37^a is adapted to be slidably applied over the free end of the post 34 and a U-shape lock or keeper 38 having a short leg 38^a and a long leg 38^b with an enlarged upset or mashed out end 38^c, and having the opposed faces of 120 its legs spaced from each other at a distance slightly less than the width of said post 34 is slidably mounted in transverse perforations in said keeper 38 in such location that, in locking position and when the keeper is 125 arranged on the post 34, the short leg 38^a will lie in one of the notches 30 of said post and so prevent movement of the keeper 38 in either direction endwise of said post 34. To release, to permit such movement of the keeper 130

38, it is simply necessary to shove on the end 38^a of the long leg 38^b to move the locking means transversely to the position indicated in dotted lines in Figure 11, when the short leg 38^a will be moved to inoperative position out of the path of said post 34.

To compress a free valve spring the keeper 37 will be entirely removed, the valve spring will be slipped over the end of the post 34 with 10 its lower end resting against the upper edges of the upper inner end portions 32 of the plates 1. The keeper 37, with the lock 38 in the dotted line position shown in Figure 11, will then be slipped over the end of post 34 15 with its flanges 37^a presented toward the upper end of the spring, and may be forced down by hand against the spring to slightly compress it, the locking means 38 then being moved to locking position as shown in solid 20 lines in Figure 11, the parts then all being in the positions shown in Figure 8, when the lever 21 will be pressed toward the handle 6 to the position shown in Figure 9, resulting in pulling the post 34 endwise between the upper 25 inner end portions 32 of plates 1 and so compressing the spring between the keeper 37 and said end portions, all as shown in Figure 9.

Thus it will be seen that the frame, parallel 30 movement links and operating lever combine both with the foot and jaw and with the post 34 to perform two functions either simultaneously or separately, or alternately, so that the one tool may be used for the two purposes.

Throughout all parts have been designed 35 for manufacture from sheet metal or from heavier narrow strap or thin bar metal, this being preferred as making for economical manufacture on a large production basis. 40 However, while preferred, it is not essential, and any suitable materials may be used for any parts and the manufacture may be in any practical manner.

Claims:

1. A valve-spring lifting and compressing tool comprising a frame, a positioning handle rigidly secured thereto intermediate the ends thereof and extending outwardly therefrom to the side thereof, a pair of removable interchangeable jaw members rigidly secured to said frame in opposed and registering relation to each other to together constitute a jaw to engage under a valve-spring retaining cup, means for relatively adjusting said members transversely, a sleeve, parallel movement links pivotally connected to said frame and pivotally connected to said sleeve, a shank adjustable slidably in said sleeve, means for locking said shank and sleeve together in any one of a number of positions of lengthwise adjustments of the former in the latter, a foot secured to said shank against axial movement thereof and adapted to rest on a valve head when said jaw is arranged about the stem of said valve under the valve-spring retaining

cup thereon, a post pivotally connected to one of said parallel movement links and extending through and guided by said frame, a head slideable on said post, and means for locking said head to said post in any one of 70 several positions of adjustment lengthwise thereof for the purpose of compressing an otherwise free valve-spring between the opposed faces of said head and the adjacent portion of said frame, in combination with a long channel sheet metal operating lever pivotally connected to said frame above, and inward of, the points of pivotal connection thereto of said parallel movement links, a pair of short thrust links spanning one of said parallel movement links and having their lower ends connected together and pivotally to the other of said links, a pivot pin extending through the lower portions of said thrust links and the intervening portion of the latter parallel movement link at a point between the side and upper inner end of said frame, the upper ends of said thrust links being in engagement and lying between the sides of 80 said operating lever, a pivot pin extending through said sides of said lever and the intervening upper end portions of said thrust links at a point to the rear of, and closely adjacent to, the point of pivotal connection of 85 said lever to said frame, whereby a movement of said operating lever toward said handle results in a powerful thrust on one of said parallel movement links with a resultant movement of the frame as a whole and in a straight line toward said foot, a tongue pivotally connected to said lever to the rear of the pivotal point of connection of the thrust links thereto and extending through said handle, said tongue having its outer edge face formed with a plurality of spaced notches, a slotted plate having the rear wall of said slot so positioned as to engage in said notches, a pivot pin pivotally connecting said plate to said handle adjacent said frame, and resilient 95 means bearing against said handle and the opposed face of said plate to normally hold the latter in locking position to lock the operating lever in any one of several positions while permitting the downward yielding of said plate toward said handle as the tongue 100 is moved downward through said handle.

2. A valve-spring lifting and compressing tool comprising a frame, a positioning handle rigidly secured thereto intermediate the ends thereof appreciably below the upper end thereof and extending outwardly therefrom to the side thereof, a jaw carried by said frame to engage under a valve-spring retaining cup, a sleeve, parallel movement links pivotally connected to said frame and pivotally connected to said sleeve, a shank adjustable slidably in said sleeve, means for locking said shank and sleeve together in any one of a number of positions of lengthwise adjustments of the former in the lat- 110 115 120 125 130

ter, a foot secured to said shank against axial movement thereof and adapted to rest on a valve head when said jaw is arranged about the stem of said valve under the valve-spring retaining cup thereon, a post pivotally connected to one of said parallel movement links and extending through and guided by said frame, a head slideable on said post, and means for locking said head to said post in any one of several positions of adjustment lengthwise thereof for the purpose of compressing and otherwise free valve-spring between the opposed faces of said head and the adjacent portion of said frame, in combination with a long channel sheet metal operating lever pivotally connected to said frame above, and inward of, the points of pivotal connection thereto of said parallel movement links, a pair of short thrust links spanning one of said parallel movement links and having their lower ends connected together and pivotally to the other of said links, a pivot pin extending through the lower portions of said thrust links and the intervening portion of the latter parallel movement link at a point between the side and upper inner end of said frame, the upper ends of said thrust links being in engagement and lying between the sides of said operating lever, a pivot pin extending through said sides of said lever and the intervening upper end portions of said thrust links at a point to the rear of, and closely adjacent to, the point of pivotal connection of said lever to said frame, whereby a movement of said operating lever toward said handle results in a powerful thrust on one of said parallel movement links with a resultant movement of the frame as a whole and in a straight line toward said foot, a tongue pivotally connected to said lever to the rear of the pivotal point of connection of the thrust links thereto and extending through said handle, said tongue having its outer edge face formed with a plurality of spaced notches, a slotted plate having the rear wall of said slot so positioned as to engage in said notches, a pivot pin pivotally connecting said plate to said handle adjacent said frame, and resilient means bearing against said handle and the opposed face of said plate to normally hold the latter in locking position to lock the operating lever in any one of several positions while permitting the downward yielding of said plate toward said handle as the tongue is moved downward through said handle.

3. A valve-spring lifting and compressing tool comprising a frame, a positioning handle rigidly secured thereto considerably below the upper end thereof and extending outwardly therefrom to the side thereof, a jaw carried by said frame to engage under a valve-spring retaining cup, a sleeve, parallel movement links pivotally connected to said frame and pivotally connected to said sleeve, a shank adjustable slidably in said sleeve, and a foot secured to said shank against axial movement thereof and adapted to rest on a valve head when said jaw is arranged about the stem of said valve under the valve-spring retaining cup thereon, in combination with a long operating lever pivotally connected to said

frame and pivotally connected to said sleeve, a shank adjustable slidably in said sleeve, and a foot secured to said shank against axial movement thereof and adapted to rest on a valve head when said jaw is arranged about the stem of said valve under the valve-spring retaining cup thereon, in combination with a long channel sheet metal operating lever pivotally connected to said frame above, and inward of, the points of pivotal connection thereto of said parallel movement links, a pair of short thrust links spanning one of said parallel movement links and having their lower ends connected together and pivotally to the other of said links, a pivot pin extending through the lower portions of said thrust links and the intervening portion of the latter parallel movement link at a point between the side and upper inner end of said frame, the upper ends of said thrust links being in engagement and lying between the sides of said operating lever, a pivot pin extending through said sides of said lever and the intervening upper end portions of said thrust links at a point to the rear of, and closely adjacent to, the point of pivotal connection of said lever to said frame, whereby a movement of said operating lever toward said handle results in a powerful thrust on one of said parallel movement links with a resultant movement of the frame as a whole and in a straight line toward said foot, a tongue pivotally connected to said lever to the rear of the pivotal point of connection of the thrust links thereto and extending through said handle, said tongue having its outer edge face formed with a plurality of spaced notches, a slotted plate having the rear wall of said slot so positioned as to engage in said notches, a pivot pin pivotally connecting said plate to said handle adjacent said frame, and resilient means bearing against said handle and the opposed face of said plate to normally hold the latter in locking position to lock the operating lever in any one of several positions while permitting the downward yielding of said plate toward said handle as the tongue is moved downward through said handle.

4. A valve-spring lifting and compressing tool comprising a frame, a positioning handle rigidly secured thereto intermediate the ends thereof and extending outwardly therefrom to the side thereof, a jaw carried by said frame to engage under a valve-spring retaining cup, a sleeve, parallel movement links pivotally connected to said frame and pivotally connected to said sleeve, a shank adjustable slidably in said sleeve, and a foot secured to said shank against axial movement thereof and adapted to rest on a valve head when said jaw is arranged about the stem of said valve under the valve-spring retaining cup thereon, in combination with a long operating lever pivotally connected to said

frame above, and inward of, the points of pivotal connection thereto of said parallel movement links, a thrust link, a pivot pin pivotally connecting one end of said thrust link to one of said parallel movement links at a point between the side and upper inner end of said frame, a pivot pin pivotally connecting the other end of said thrust link to said lever at a point to the rear of, and closely adjacent to, the point of pivotal connection of said lever to said frame, whereby a movement of said operating lever toward said handle results in a powerful thrust on one of said parallel movement links with a resultant movement of the frame as a whole and in a straight line toward said foot, a tongue pivotally connected to said lever to the rear of the pivotal point of connection of the thrust links thereto and extending through said handle said tongue having its outer edge face formed with a plurality of spaced notches, a slotted plate having the rear wall of said slot so positioned as to engage in said notches, a pivot pin pivotally connecting said plate to said handle adjacent said frame, and resilient means bearing against said handle and the opposed face of said plate to normally hold the latter in locking position to lock the operating lever in any one of several positions while permitting the downward yielding of said plate toward said handle as the tongue is moved downward through said handle.

5. A valve-spring lifting and compressing tool comprising a frame, a positioning handle rigidly secured thereto intermediate the ends thereof and extending outwardly therefrom to the side thereof, a jaw carried by said frame to engage under a valve-spring retaining cup, parallel movement links pivotally connected at one end to said frame, means to which the other ends of said parallel movement links are pivotally connected, and a foot carried by said means and relatively immovable and adapted to rest on a valve head when said jaw is arranged about the stem of said valve under the valve-spring retaining cup thereon, in combination with an operating lever pivotally connected to said frame above, and inward of, the points of pivotal connection thereto of said parallel movement links, a pivot pin pivotally connecting one end of said thrust link to one of said parallel movement links, a pivot pin pivotally connecting the other end of said thrust link to said lever at a point to the rear of, and closely adjacent to, the point of pivotal connection of said lever to said frame, and cooperating means carried by said lever and handle for locking said lever in any one of a number of positions.

6. A valve-spring lifting and compressing tool comprising a frame, a positioning handle rigidly secured thereto intermediate the ends thereof and extending outwardly therefrom to the side thereof, a jaw carried by said

frame to engage under a valve-spring retaining cup, parallel movement links pivotally connected at one end to said frame, means to which the other ends of said parallel movement links are pivotally connected, and a foot carried by said means and immovable with relation thereto and adapted to rest on a valve head when said jaw is arranged about the stem of said valve under the valve-spring retaining cup thereon, in combination with an operating lever pivotally connected to said frame above, the point of pivotal connection thereto of said parallel movement links, a short link, a pin pivotally connecting one end of said short link to one of said parallel movement links, a pin pivotally connecting the other end of said short link to said lever, and means for locking said lever in operative position.

7. A valve-spring lifting tool comprising a frame, a handle rigidly secured thereto intermediate the ends thereof and extending outwardly therefrom to the side thereof, a jaw carried by said frame to engage under a valve-spring retaining cup, parallel movement links pivotally connected at one end to said frame, a rigid part to which the other ends of said parallel movement links are pivotally connected, and a foot carried by said part and operatively immovable with relation thereto and adapted to rest on a valve head when said jaw is arranged about the stem of said valve under the valve-spring retaining cup thereon, in combination with an operating lever pivotally connected to said frame above the points of pivotal connection thereto of said parallel movement links, and a short thrust link, having its ends respectively pivotally connected to one of said parallel movement links and to said lever.

8. A valve-spring lifting tool comprising a frame, a handle rigidly secured thereto intermediate the ends thereof and extending outwardly therefrom to the side thereof, a jaw carried by said frame to engage under a valve-spring retaining cup, a foot adapted to rest on a valve head when said jaw is arranged about the stem of said valve under the valve-spring retaining cup thereon, and movable means connecting said frame and foot, in combination with an operating lever pivotally connected to said frame, a short thrust link, having its ends respectively pivotally connected to said means and said lever, and means for locking said lever in operative position.

9. A valve-spring lifting tool comprising a frame, a handle rigidly secured thereto intermediate the ends thereof and extending outwardly therefrom to the side thereof, a jaw carried by said frame to engage under a valve-spring retaining cup, a foot adapted to rest on a valve head when said jaw is arranged about the stem of said valve under the valve-spring retaining cup thereon, and

movable means connecting said frame and foot, in combination with an operating lever pivotally connected to said frame, and a short thrust link, having its ends respectively pivotally connected to said means and said lever.

10. A valve-spring lifting tool comprising a frame, a handle rigidly secured thereto intermediate the ends thereof and extending outwardly therefrom to the side thereof, a jaw carried by said frame to engage under a valve-spring retaining cup, a foot adapted to rest on a valve head when said jaw is arranged about the stem of said valve under the valve-spring retaining cup thereon, and movable means connecting said frame and foot, in combination with an operating lever pivotally connected to said frame, a short thrust link, having its ends respectively pivotally connected to said means and said lever, and

15 a post connected to said means and movable through said frame with said means for compressing an otherwise free valve-spring.

11. A valve-spring lifting tool comprising a frame, a handle rigidly secured thereto intermediate the ends thereof and extending outwardly therefrom to the side thereof, a jaw carried by said frame to engage under a valve-spring retaining cup, a foot adapted to rest on a valve head when said jaw is arranged about the stem of said valve under the valve-spring retaining cup thereon, and mov-

able means connecting said frame and foot, in combination with an operating lever pivotally connected to said frame, a short thrust link, having its ends respectively pivotally connected to said means and said lever, and an element connected to said means, cooperating with said frame and moving with said means and adapted to compress an otherwise free valve-spring.

12. A valve-spring lifting tool comprising a frame, a handle secured thereto, a jaw carried by said frame to engage under a valve-spring retaining cup, a foot adapted to rest on a valve head when said jaw is arranged about the stem of said valve under the valve-spring retaining cup thereon, and movable means connecting said frame and foot, in combination with an operating lever pivotally connected to said frame, a short thrust link, having its ends respectively pivotally connected to said means and said lever, and an element connected to said means, movable through said frame and cooperating therewith, and moving with said means and adapted to compress an otherwise free valve-spring.

In testimony whereof, we have signed our names to this specification at Lancaster, Pennsylvania, this 20th day of July, 1927.

HARRY W. KULP.
MARTIN C. DELLINGER.
